FEATHER PLUCKING MACHINE

Raleigh F. Lane, Jr., 1/3 Third National Bank, and
Alexander J. Baird, 3503 Echo Hill Road, both of
Nashville, Tenn. 37215

Filed Feb. 2, 1972, Ser. No. 223,047

Term of patent 14 years

Int. Cl. D15—08

U.S. Cl. D55—1 E

FIG1

FIG5

FIG2

FIG3

FIG4

FIG. 1 is a front elevational view of the feather plucking machine showing our new design;

FIG. 2 is an elevational view of the left end thereof;
FIG. 3 is an elevational view of the right end thereof;
FIG. 4 is a rear elevational view thereof; and

FIG. 5 is a top plan view thereof.

We claim:

The ornamental design for a feather plucking machine, as shown.
